UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

HOPPER-CAR.

1,281,286.

Specification of Letters Patent. Patented Oct. 15, 1918.

Application filed May 14, 1917. Serial No. 168,401.

To all whom it may concern:

Be it known that I, ARGYLE CAMPBELL, a citizen of the United States, residing at Chicago, in the county of Cook and State of Illinois, have invented a certain new and useful Improvement in Hopper-Cars, of which the following is a full, clear, concise, and exact description, reference being had to the accompanying drawings, forming a part 10 of this specification.

This invention relates to improvements in hopper cars.

Heretofore, in the use of hopper cars, and more particularly ore cars, great difficulty 15 has been experienced in cold weather in discharging the loads from the cars due to the fact that the ore or other material in bulk freezes and "bridges," thus preventing proper discharge from the hoppers. To 20 overcome this, the operators must either get into the cars and use a crow-bar or other suitable tool to break down the ore, which is a tedious and expensive operation or, the practice has sometimes been employed of in- 25 troducing a steam jet into the body of frozen ore. The latter process requires that the steam be injected into the ore at different points and is an inefficient operation inasmuch as the greater portion of the steam 30 escapes and furthermore, it is difficult to introduce the steam in the middle or central portions of the load where the ore should be first thawed out.

One object of my invention is to provide 35 an efficient arrangement of hopper car or ore car which permits the application of heat, as by means of steam, to the load within the hopper to expedite thawing out the frozen ore or other material and thus facilitate its discharge from the hoppers.

Another and more specific object of the invention is to provide a hopper car having steam passageways extending around and also through the hoppers and without sacrificing any of the load-carrying capacity of 45 the car to thereby increase the rapidity with which the load may be thawed out.

Further objects of the invention are to provide an efficient door operating mech- 50 anism more particularly adapted for cars of the type above described and also to improve and strengthen the general construction of the ore type of cars.

In the drawings forming a part of this 55 specification, Figure 1 is a part side eleva-

tion, part longitudinal section on line 1—1, Fig. 4 of an ore car showing my improvements in connection therewith. Fig. 2 is a vertical, transverse sectional view of the car illustrated in Fig. 1 and taken on the line 60 2—2 thereof, Fig. 2 being upon a larger scale than Fig. 1. Fig. 3 is a transverse sectional view, parts being broken away, the section being taken substantially on the line 3—3 of Fig. 1. Fig. 4 is a horizontal sec- 65 tional view, parts being broken away, and taken substantially on the line 4—4 of Fig. 1 and illustrating more particularly the arrangement of steam passageways. Fig. 5 is a vertical longitudinal sec- 70 tional view taken centrally of the car to illustrate the door operating arrangement. Fig. 6 is an enlarged elevation and part section of part of the door operating mech- 75 anism. And Fig. 7 is a top plan view of a portion of the door operating mechanism.

In said drawings, the hopper car is shown as comprising vertical side walls 10—10; inclined end hopper walls 11—11, built up body bolsters 12—12 (hereinafter more particularly described); center sills 13—13; Z-bar side sills 14—14; Z-bar end sills 15—15; a pair of hinged hopper doors 16—16; door operating mechanism, designated generally by the reference A; and steam passageways, 85 hereinafter described.

The side walls 10 of the car are extended down vertically and secured to the Z-bar side sills, as indicated at 17 in Fig. 2. At the lower ends of each of the side walls, inwardly and downwardly inclined plates 18—18 are employed, the latter being secured at their upper edges to the side walls 10 and at their lower edges to the inner flanges of the Z-bar side sills, as indicated 95 at 19, thereby forming outside, longitudinally extending triangular shaped passageways B—B. The inclined end hopper sheets 11—11, just above the center sills, have secured thereto vertical, transversely extend- 100 ing pressed plates 20—20, on the under sides of the end hopper walls which, in conjunc- 105 tion with horizontally and transversely ex- 110 tends plates 21—21 also form triangular shaped passageways C—C that extend transversely of the car and which are also in communication with the outside passageways B—B, as most clearly illustrated in Fig. 4. As will be understood, the trans- 110 verse passageways C—C are closed at their

outer ends by the side sheets of the car, one of the passageways C, however, having an inlet orifice 22 at one side of the car through which may be introduced a steam hose, for 5 the purpose hereinafter described. Said orifice 22 is normally closed by a pivoted cap plate 23.

The hopper of the car is divided transversely and longitudinally so as to form four 10 discharge openings, two on each side of the center sill, as will be understood from an inspection of Fig. 4. The longitudinal division is formed by a pair of inclined longitudinal sheets 24—24 mounted on the tops of 15 the center sills 13—13, as clearly appears from Fig. 2 and said sheets 24—24 in conjunction with a horizontal plate 25 mounted on the tops of the sills 13, form a center or intermediate longitudinally extending passageway D, the same being in communication 20 with the end passageways C—C, as appears from Fig. 4. The transverse division wall of the hopper is formed by a pair of transversely extending plates each having a lower 25 vertical portion 26 and an upwardly inclined portion 27, as appears from Fig. 5. The upper portions 27 of said transversely extending plates in conjunction with another horizontal transverse plate 28 form a center 30 or intermediate transversely extending passageway E, the same being in communication with the longitudinal passageways B—B and D, as clearly appears from Fig. 4. In connection with all of the foregoing described passageways, it will be understood 35 that the plates are cut away at the junction points in order to provide the necessary communication.

With the arrangement above described, it 40 is apparent that when steam or other suitable heating medium is introduced through the orifice 22, the steam will circulate entirely around the hopper closely adjacent the door openings and also through the load, both 45 longitudinally and transversely, and at the same level. In this manner, heat is applied to the load within the hopper over an extended area, thus facilitating the thawing out process. Furthermore, the steam passageways are so disposed that the load-carrying 50 capacity of the car is not lessened nor is the expense of the car construction incident to the passageways appreciably increased. It is also apparent that all of the plates employed in forming the steam passageways increase materially the strength of the car.

Each of said hopper doors 16—16 extends across two of the discharge openings and each door 16 is pivoted about a longitudinal 60 axis at the side of the car, as indicated at 29, the hinge points being located beneath the Z-bar side sills 14. Along their inner edges, the doors 16 are strengthened by suitably constructed bracing bars 30, the latter 65 being extended slightly beyond the doors at

their ends to form connecting arms for the chains 31—31. There are four chains 31, one from each end of each door, said chains 31 passing in pairs over sheave wheels 32—32 located between the center sills and at opposite sides of the longitudinal center of the car and mounted in suitable bearing brackets 33—33 riveted to the center sills. Each set of chains is properly guided on the sheave wheel by a central annular rib 34. The ends 70 of each pair of chains 31 are connected to a balancing or equalizing link 35, each link 35 in turn being connected to a hook-shaped link 36, the latter in turn being pivotally connected to a short link 37, each short link 80 37 being connected to another link 38 and each of the latter in turn being connected to a lever arm 39 formed integrally with a hub 40 mounted on a transversely extending operating shaft 41. As clearly appears from 85 Fig. 6, one set of links, 36, 37 and 38, winds under the shaft 41 and the other set over the shaft 41 in closely adjacent vertical planes to thereby neutralize the torsion on the shaft when the doors are in closed position. As 90 will be understood, the hub 40 and links immediately associated therewith, together with the inner ends of the chains 31, are located between the center sills, and in order to provide the necessary clearance for the 95 ends of the lever arms 39 when the shaft 41 is rotated, the cover plate 25 is cut away, as indicated at 42 in Fig. 4, and while this opening 42 may permit escape of a slight amount of steam, the amount which can pass 100 therethrough is comparatively small and may be neglected in actual practice.

The shaft 41 is extended to both sides of the car and is provided with suitable squared ends 43 by which it may be rotated in the 105 usual manner by a claw-bar or other suitable tool. The operating shaft 41 is provided with suitable ratchet and pawl mechanism, the latter being operable from either side of the car by means of a transversely extending auxiliary shaft 44 which extends through the central passageway E. A detailed description of the pawl and dog mechanism which is operable from either side of the car, will be found in my patent for improvement in door operating mechanism, No. 1,255,385 granted February 5, 1918.

Each of the bolsters of the car comprises a vertically extending plate 45, said plate extending up to the inclined end wall 11 of the hopper and being suitably reinforced by vertically extending angles 46 and also at the bottom by horizontally extending angles 47. Each of the bolsters 12 is also braced by suitable plates and angles 48 extending from the vertical plate 45 to the adjacent inclined end wall 11 of the hopper. At the ends of each of the hopper doors 16, near the outer sides thereof adjacent the hinges, downwardly extending plates 49—49 125 130

are provided to prevent discharge of any of the load to the outer sides of the rails and thus insure the complete discharge of the load within the rails when the doors 16
5 swing open.

Although I have herein shown and described what I now consider the preferred manner of carrying out my invention, the same is merely illustrative and I contemplate 10 all changes and modifications that come within the scope of the claims appended hereto.

I claim:

1. A hopper car having inclined end hopper sheets, transversely extending vertical and horizontal sheets beneath said end hopper sheets and forming therewith transversely extending passageways adapted to receive a heating medium therewithin.
- 20 2. A hopper car having inclined end hopper sheets, transversely extending vertical and horizontal sheets beneath said end hopper sheets and forming therewith transversely extending passageways adapted to receive a heating medium therewithin, and 25 a longitudinally extending passageway in

communication with said transversely extending passageways.

3. A car of the character described having a central hopper and three transversely extending triangularly shaped passageways and three longitudinally extending triangularly shaped passageways, the intermediate longitudinal and intermediate transverse passageways extending through the hopper 35 and being relatively shallow, said passageways being adapted to have a heating medium introduced therewithin.

4. In an ore car, the combination with a single hopper divided longitudinally by the 40 center sill and transversely by a transverse partition, of steam passageways extending around and through said hopper, said transverse partition being utilized for one of said steam passageways, of hopper doors, and devices for operating said doors including 45 means disposed within said transversely extending partition.

In witness that I claim the foregoing I have hereunto subscribed my name this 50 28th day of April, 1917.

ARGYLE CAMPBELL.
